UNITED STATES PATENT OFFICE.

HIPPOLYT SAURER, OF ARBON, SWITZERLAND.

JACQUARD-CARD-PUNCHING MACHINE.

1,104,550.

Specification of Letters Patent.

Patented July 21, 1914.

Application filed February 27, 1913. Serial No. 750,952.

To all whom it may concern:

Be it known that I, HIPPOLYT SAURER, a citizen of the Republic of Switzerland, residing at Arbon, Switzerland, have invented 5 new and useful Improvements in Jacquard-Card-Punching Machines; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention has reference to improvements in machines for punching holes in the pattern cards used for controlling the automatic frame-moving mechanism in jac- quard embroidery machines.

20 In one type of punching machine the perforations to be made in the cards are determined by means of drums, which are provided either with holes or with pins, accord- 25 ing to a definite system. Each such ma- chine has at least two drums, by one of which punches are selected for piercing in the card those holes by means of which the horizontal movements of the work-frame are subsequently caused in the embroidery 30 machine, while the second drum selects punches which pierce the holes by means of which the vertical movements of the frame are produced. The manner in which this 35 is done is disclosed in Letters Patent of the United States No. 1,055,893, dated March 11, 1913, where two such drums, furnished with pins, are shown, and in which is explained how, by adjustment of these drums, the holes can be variously punched in the jac- 40 quard card, and also how the work-frame of an embroidery machine can be operated with the aid of this card. It is necessary each time after perforating to return the 45 drums to their "zero" position, that is, that position in which there are no drum- 50 pins (or holes) opposite the needles, and the present invention consists in improved mechanism for effecting this return. For this purpose each drum is rigidly connected with a heart-shaped cam, and means are provided which can be caused to exert pres- 55

tion are illustrated in the accompanying drawings in which—

Figure 1 is a side elevation, showing such parts of a punching machine as are necessary for a proper understanding of the present invention. Fig. 2 is a plan of Fig. 1. Fig. 3 is a detail sectional view, showing the drum-returning mechanism drawn on a larger scale. Fig. 4 is an elevation of the same mechanism viewed at a right angle to Fig. 3. Fig. 5 is a plan of another embodiment of the invention, and Fig. 6 is an elevation thereof, drawn on a larger scale.

Referring to the first embodiment, as shown in Figs. 1-4, 1^a and 1^b are the two 70 drums, both provided with holes 1^c according to a definite system. The drums are rotatable independently, for instance in the manner described in Letters Patent of the United States No. 1,055,893, dated March 11, 1913, 75 already above referred to. With each drum there is rigidly connected a heart-cam 2^a, 2^b respectively, provided with a notch 2^e. When the drum is in the zero position, the cam notch is uppermost, as shown in full 80 lines in Fig. 3. Rigidly secured to the machine frame 3 is a bracket 10, forming a guide for the vertically reciprocal rod 4. At the lower end of this rod there is mounted a roller 5, while the top end is fur- 85 nished with a pin 11, which engages in the slot 12 at the extremity of a lever 6. Such rod and lever mechanism is provided above each heart-cam 2^a, 2^b, and both levers 6 are fixed on a shaft 7, which carries a lever 8 90 outside the frame 3 provided with a pin 9. This pin enters the groove of a cam 13, mounted on a shaft 14, which is driven continuously from any suitable source of power by means of a sprocket wheel 15 or the like. 95

When the two drums 1^a, 1^b have been ad- justed, the one being for instance so set, that the heart-cam occupies the position shown in broken lines in Fig. 3, then on the pin 9, during rotation of the grooved cam 13, being 100 received by the laterally deviating part 16 of the track, both levers 6 will be moved downward and the rollers 5 of the rods 4 will be pressed down upon the tracks of the heart-cams 2^a, 2^b, whereby the drums 1^a, 1^b 105 will be turned, until the rollers 5 enter the notches 2^e. When this occurs the drums will have been returned to the zero position again.

In the modification shown in Figs. 5 and 110

6, the mechanism is substantially the same as that above described, except that there is only one lever 6 mounted on the shaft 7. This lever is connected to a rod 4 which carries two rollers 5 at its lower end, each of which is located above one of the heart-cams 2^a, 2^b. In this construction, therefore, both drums 1^a, 1^b can be turned to the zero position simultaneously by a single lever.

10 Having thus described my invention, I claim as new—

15 1. In a jacquard card punching machine, a drum, means for rotatively setting the drum according to the manner in which the card is to be punched, a cam rigidly connected with the drum, and means for exerting pressure in a radial direction upon the track of the cam for the purpose of returning the drum to the zero position.

20 2. In a jacquard card punching machine, a plurality of drums, means for rotatively setting the drums according to the manner in which the card is to be punched, a cam rigidly connected with each drum, and 25 means for exerting pressure in a radial direction upon the tracks of the cams for the purpose of returning the drums to the zero position.

30 3. In a jacquard card punching machine, a plurality of drums, means for rotatively setting the drums according to the manner in which the card is to be punched, a heart-cam rigidly connected with each drum, and means for exerting pressure in a radial 35 direction upon the track of the cams, for the purpose of returning the drums to the zero position.

40 4. In a jacquard card punching machine, a plurality of drums, means for rotatively setting the drums according to the manner

in which the card is to be punched, a heart-cam rigidly connected with each drum, lever mechanism adapted to exert pressure in a radial direction upon the tracks of the cams, and means for actuating the said mechanism, for the purpose of returning the drums to the zero position. 45

5. In a jacquard card punching machine, a plurality of drums, means for rotatively setting the drums according to the manner in which the card is to be punched, a heart-cam rigidly connected with each drum, a lever carrying two rollers, one located above the track of each cam, and means for actuating the said lever, whereby the rollers are 50 pressed upon the cam tracks in a radial direction, for the purpose of returning the drums to the zero position.

6. In a jacquard card punching machine, a plurality of drums, means for rotatively setting the drums according to the manner in which the card is to be punched, a cam rigidly connected with each drum, levers bearing on said cams, a rock shaft on which the levers are carried, an independent cam, 60 means to rotate the same continuously, an independent lever carried by said rock shaft and co-operating with the last named cam whereby upon each revolution of the latter the rock shaft is oscillated to press the first 65 named levers upon their respective cams in radial direction for the purpose of returning the drums to the zero position. 70

This specification signed and witnessed this 24th day of February, A. D., 1913.

HIPPOLYT SAURER.
